TOOTHPICK DISPENSER

Earcy Ballard, San Diego, Calif.

Application November 30, 1937, Serial No. 177,338

6 Claims. (Cl. 312—76)

My invention relates to an apparatus for dispensing toothpicks to the public, and the objects of my invention are:

First, to provide a dispenser for toothpicks in which only a single toothpick is dispensed at a time, thus making the toothpick dispenser very sanitary;

Second, to provide a dispenser of this class in which after the toothpick has been removed, or 10 partially removed, it cannot be put back into the dispenser;

Third, to provide a toothpick dispenser of this class which will hold a large number of toothpicks at one time;

15 Fourth, to provide a toothpick dispenser of this class in which the toothpicks may be seen but cannot be handled except when they are dispensed one at a time.

Fifth, to provide a dispenser of this class which is interesting to operate;

20 Sixth, to provide a dispenser of this class in which the toothpicks are automatically held in close relation so that they are easily dispensed; and

25 Seventh, to provide a dispenser of this class which is very simple and economical of construction, easy to operate, sanitary in its action, and which will not readily deteriorate or get out of order.

30 With these and other objects in view as will appear hereinafter, my invention consists of certain novel features of construction, combination, and arrangement of parts and portions as will be hereinafter described in detail and particularly set forth in the appended claims, reference being had to the accompanying drawing and to the characters of reference thereon which form a part of this application in which:

Figure 1 is a front elevational view of my toothpick dispenser complete; Fig. 2 a top or plan view thereof; Fig. 3 a longitudinal sectional view taken from the line 3—3 of Fig. 2 showing some of the parts and portions in elevation to facilitate the illustration; and Fig. 4 is a transverse sectional view taken from the line 4—4 of Fig. 2 showing some of the parts and portions in elevation to facilitate the illustration.

Similar characters of reference refer to similar parts and portions throughout the several views of the drawing:

The toothpick receptacle sides 1 and 2, toothpick receptacle base 3, toothpick receptacle back 4, toothpick selector support 5, toothpick selector supporting spring 6, toothpick selector handle 7, toothpick selector member 8, toothpick selector

member return spring 9, toothpick receptacle front 10, toothpick receptacle cover 11, and resilient members 12 and 13 constitute the principal parts and portions of my toothpick dispenser.

The toothpick receptacle side members 1 and 2 are positioned on inclined relation to each forming a V-shape sided receptacle as shown best in Fig. 4 of the drawing. They are secured together at their lower edges by means of beveled corners 1a and 2a so that the intersection of the inner sides is raised some distance from the lower side, and the lower sides rest in a recess 3a in the base member 3, all as shown best in Fig. 4 of the drawing. This base member 3 is preferably rectangular in shape and extends forwardly and backwardly of the side members of the receptacle as shown best in Figs. 2 and 3 of the drawing. These side members 1 and 2 are secured in their certain relation to each other by means of the back 4, which rests on top of the base 3 and extends to the upper side of the side members 1 and 2.

Secured on the backwardly extending portion 3b of the base member 3 is the toothpick selector support 5, which is also secured to the back member 4 and extends upwardly some distance above of the side members 1 and 2 and back member 4, and serves as a reinforcement between the base 3 and the back member 4. The upper end of this member 5 is turned over the receptacle by a right angle turn 5a and is provided with a loop 5b in its extended end. This member 5 is preferably made of a metallic strip and the loop portion 5b is considerably narrower than the body portion. Mounted in the loop portion 5b of the member 5 is a tension spring 6 at one of its ends, and its other end connects with a loop member 7a secured in the one end of the handle 7. Thus it will be noted that the handle 7 may be lowered by slightly stretching the spring 6. Mounted in this loop member 7a is also another spring 9 which extends substantially at right angles to the spring 6 on a substantially horizontal plane and is secured to the body portion of the member 5. This spring 9 is for the purpose of returning the handle member to a backward position after the toothpick has been selected and moved forwardly out of the receptacle and the handle released.

Also secured in the handle 7 at the backward end adjacent to the loop member 7a is the toothpick selector member 8, which is a long thin metal member provided with a slightly broadened knife edge end 8a, and it is provided slightly above the end with oppositely disposed lugs 8b which prevent the selector member from

coming out of a slot 11a in the cover member 11. This cover member 11 is preferably transparent and is supported on the upper edges of the side members 1 and 2 by means of screws 11b so that 5 the member 11 may slide forwardly for placing toothpicks in the receptacle formed by the side members 1 and 2 and back member 4; or this top member 11 may be secured by means of screws so that the receptacle is not accessible except by 10 removing these screws 11b.

Secured on the front edges of the side members 1 and 2 with its lower side extending down into the recess 3a, is the receptacle front member 10. This receptacle front member 10 is preferably composed of thin sheet metal shaped to conform to the outer sides of the members 1 and 2 and secured thereto by means of screws 10a. It is reinforced at its upper edge by a thicker metallic plate 10b for supporting said upper edge. This 20 front member 10 is provided with a vertical slot 10c extending from near the top to near the bottom at the middle between the members 1 and 2 and is provided with a plurality of cross slots 10d. These slots are slightly narrower than the toothpicks 25 are thick so that the material surrounding the slots is pressed outwardly when a toothpick is pressed outwardly by the selecting member 8, and the sides adjacent said slots engage the sides of the toothpick and thereby prevent the toothpick from being pressed inwardly but permit its ready withdrawal.

In order to keep the toothpicks bunched there are provided two pairs of slots in each of the side members which are designated 1b and 2b, which 35 extend from the tops of said side members to near the bottoms thereof, and in which are mounted rubber bands, or other resilient members 12 and 13, which are stretched over the toothpicks when they are placed in the receptacle, and as the toothpicks are moved from the receptacle, these members tighten down on and keep the toothpicks bunched in the bottom of the receptacle as shown best in Fig. 4 of the drawing.

45 The operation of my toothpick dispenser is as follows: The receptacle between members 1 and 2 is substantially filled with toothpicks and the rubber bands placed thereover. When it is desired to take a toothpick from the receptacle, the 50 handle 7 is grasped and the end 8a of the member 8 is engaged with a toothpick and the handle drawn forwardly. It carries with it a toothpick which passes out through one of the slots 10c or 10b, and the end of the toothpick which protrudes 55 may be grasped and withdrawn, but cannot be pressed back into the receptacle. The handle may be released after the toothpick has been started outwardly.

Though I have shown and described a particular construction, combination, and arrangement of parts and portions, I do not wish to be limited to this particular construction, combination, and arrangement, but desire to include in the scope of my invention, the construction, combination and arrangement substantially as set forth in the appended claims.

Having thus described my invention, what I claim as new and desire to secure by Letters Patent is:

70 1. In a toothpick dispenser of the class described, the combination of a V-shaped receptacle provided with a base and with slots in one end, a cover therefore provided with a slot in the middle thereof longitudinal of said receptacle, a selector support secured to said receptacle and

extending over said longitudinal slot, a selector member mounted in said longitudinal slot, a tension spring connected to said support at its upper end and to said selector member at its lower end, a handle member secured to said selector member and extending forwardly of said receptacle, and a retraction tension spring in connection with said handle and with said support positioned on a horizontal plane.

2. In a toothpick dispenser of the class described, the combination of a V-shaped receptacle provided with a base and with slots in one end, a cover therefor provided with a slot in the middle thereof longitudinal of said receptacle, a selector support secured to said receptacle and 10 extending over said longitudinal slot, a selector member mounted in said longitudinal slot, a tension spring connected to said support at its upper end and to said selector member at its lower end, a handle member secured to said selector member and extending forwardly of said receptacle, a retraction tension spring in connection with said handle and with said support positioned on a horizontal plane, 15 said receptacle provided with slots in its side walls and resilient members mounted in said slots adapted to engage the upper sides of the toothpicks to hold them bunched.

3. In a toothpick dispenser of the class described, the combination of a V-shaped receptacle provided with a base, a cover therefor provided with a slot in the middle thereof longitudinal of said receptacle, a selector support secured to said receptacle and extending over said longitudinal slot, a selector member mounted in said longitudinal slot, a tension spring connected to said support at its upper end and to said selector member at its lower end, a handle member secured to said selector member and extending forwardly of said receptacle, a retraction tension 30 spring in connection with said handle and with said support positioned on a horizontal plane, 35 said receptacle provided with slots in its side walls and resilient members mounted in said slots adapted to engage the upper sides of the toothpicks to hold them bunched, and a yieldable metallic front provided with vertical and horizontal slots in the middle portion thereof of 40 smaller size than the toothpicks.

4. In a toothpick dispenser of the class described, the combination of a V-shaped receptacle provided with a base, a cover therefor provided with a slot in the middle thereof longitudinal of said receptacle, a selector support secured to said receptacle and extending over said 50 slot, a selector member mounted in said slot, a tension spring connected to said support at its upper end and to said selector member at its lower end, a handle member secured to said selector member and extending forwardly therefrom and a yieldable metallic front provided with vertical and horizontal communicating slots in the middle thereof of smaller size than the toothpicks.

5. In a toothpick dispenser, a receptacle provided with a base, a cover therefor provided with a slot therein longitudinal of said receptacle, a selector member adapted to fit in said slot and engage one of said toothpicks, a handle for said selector member, a support for said selector member mounted on the base and cooperating with the base to support said receptacle and said support being extended over said receptacle, a spring connecting said support with said selector member, a front for said receptacle provided with a 70 75 80 85 90 95 100 105 110 115 120 125 130 135 140 145 150 155 160 165 yieldable portion provided with intersecting slots therein of smaller size than the toothpicks.

6. In a toothpick dispenser, a receptacle provided with a base, a cover therefor provided with a slot therein longitudinal of said receptacle, a selector member adapted to fit in said slot and engage one of said toothpicks, a handle for said selector member, a support for said selector member mounted on the base and cooperating with the base to support said receptacle and said support being extended over said receptacle, a spring connecting

said support with said selector member, a front for said receptacle provided with a yieldable portion provided with intersecting slots therein of smaller size than the toothpicks, and yieldable means positioned around said toothpicks in said receptacle and around said base and adapted to be supported by the upper side of the stack of toothpicks and by said base, the side walls of said receptacle being slotted to accommodate said yieldable means. 5

EARCY BALLARD.
